[57] ABSTRACT

A method of cleaning, especially removing undesired solid particles, from a wet-treated textile web, especially a printed web, continuously guided over rollers, wherein the textile web is guided past individual brushes over its entire width, at brief intervals or spacing, at those locations where the opposite face of the textile web travels over a web support, and directly thereafter this textile web is flushed.

**METHOD FOR CLEANING, ESPECIALLY THE
REMOVAL OF UNDESIRED SOLID PARTICLES
FROM A CONTINUOUSLY GUIDED
WET-TREATED TEXTILE WEB, ESPECIALLY
PRINTED WEBS**

BACKGROUND OF THE INVENTION

The present invention relates to a new and improved method of cleaning, especially for removing undesired solid particles from a wet-treated textile web continuously guided over rollers, especially a printed textile web.

Following the wet treatment of webs formed of textile material it is oftentimes necessary to free such from certain substances or materials. These substances or materials which are to be freed in particular constitute residues emanating from the prior treatment, for instance certain water soluble chemicals, bleaching agents, lyes and acids, but also materials emanating from the web itself such as snarls and fibers, and finally actual foreign particles or contaminants, such as for instance marking dyes, printing ink or dye thickeners, non-fixed dye residues and contaminants resulting from transport of the web or from the treatment equipment.

Now for the purpose of removing such soluble materials and insoluble solid particles there are already known to the art an entire spate of different methods and apparatuses.

For instance, one group of such state-of-the-art techniques and apparatuses is based upon the principle of forcefully spraying the textile web following the preceding wet-treatment in order to flush away the previously mentioned materials. To this end, there are employed spray nozzles or spray tubes, which experience has shown, however, do not release the solid particles adhering to the textile web. Quite to the contrary, these foreign particles, upon passage of the web through the next successive squeezing mechanism, are even more intensively pressed into the web. Moreover, these spray batteries additionally have the notable disadvantage that they require a high consumption of water, increasing the operating costs, either because of the water consumption itself or by virtue of the required pumping power or load requirements. Additionally, a further disadvantage resides in the fact that if the spraying operation is too intensive, then under circumstances, the web travel can be considerably disturbed in that folds are formed in the web, or the web, owing to this spraying operation, laterally deviates from its associated guide rolls. Particularly when washing-out printed fabrics, a too intensified liquid jet or stream impinging upon the textile web, instead of flushing away the dye residues or the like can press such into the web, thereby forming speckling or spots at the web. Finally, it should be mentioned that with the conventional spray tubes and spray nozzles it is not possible as a practical matter to uniformly spray the entire width of the textile web, a phenomenon which, owing to clogging of individual nozzles or spray openings because of contaminants in the water can even more intensively result in the formation of streaks at the treated web.

A further group of known techniques and apparatuses employs different auxiliary devices at the treatment baths themselves in order to bring about cleaning of the textile web and removal of non-desired materials therefrom. According to these prior art proposals either the treatment bath itself is placed into a state of

turbulence and/or the web is brought into an oscillatory condition within the bath. The mechanisms required to produce such turbulence or oscillations are quite complicated and expensive, especially as concerns the energy requirements for their operation. In many instances the action of such mechanisms is only effective for a brief period of time, oftentimes only for fractions of a second, and thus, the cleaning effect attainable with such mechanisms is frequently insufficient. Furthermore, such mechanisms oftentimes require a sturdy construction of the treatment equipment and they are quite subject to disturbances. Even with these prior art devices creases or folds can form at the textile web, and the travelling web can tend to laterally deviate from its associated guide- and deflecting rollers.

Finally, for the purpose of cleaning textile webs during the cleaning phase it is also known to the art to provide individual brushes which act upon the textile web. However, the use of such brushes previously was not satisfactory, either owing to the random position thereof by virtue of the design of the installation and/or the brief effective time of such brushes.

Especially in the case of printed goods the smallest adherence of the thickening mass can be poorly and generally only unsatisfactorily removed with the day known techniques and apparatuses. Since the thickening agents contain non-fixed dyes an unsatisfactory cleaning effect works in a disadvantageous manner upon the feel and the printing authenticity of the goods. An optional mechanical action, for instance squeezing, is faced with the difficulty that the released dyes soil the bottom or ground shade of the fabric.

SUMMARY OF THE INVENTION

Hence, from what has been explained above it should be recognized that the prior art is still in need of an improved method of and apparatus for cleaning, especially for removing undesired solid particles from wet-treated textile webs, which is not associated with the aforementioned drawbacks and limitations of the prior art techniques and equipment. Therefore, a primary object of the present invention is to provide new and improved techniques for effectively and reliably fulfilling the need still existent in the art and overcoming the aforementioned drawbacks of the prior art techniques and equipment contemplated to be used for these purposes.

Another and more specific object of the present invention relates to a novel method of cleaning, especially removing undesired solid particles from a wet-treated textile web which is continuously guided over rollers, especially a printed web, by means of which the previously explained drawbacks can be prevented and wherein it is possible to achieve in a most simple manner a really thorough cleaning action.

Still a further significant object of the present invention relates to a new and improved method of cleaning, especially removing undesired solid particles or materials from a wet-treated textile web in a most efficient and reliable manner and which method is relatively simple and economical to perform.

Now, in order to implement the above method aspects of this invention the method contemplated by this development resides in the features of guiding the web throughout its entire width at short intervals, at locations at which the opposite side thereof travels over a

support, past individual brushes, and directly thereafter flushing the textile web.

This technique is able to master the problems which especially arise during cleaning of printed fabrics. Since the textile web, after each brushing operation and prior to the next brushing operation, is again guided through the bath the particles released by the brushing operation are flushed away and cannot be pressed into the fabric by the next successive brushing operation. Soiling of the fabric shade and fixation of the dye or color is prevented if, as here contemplated, the goods are immediately again immersed in the washing bath following the mechanical treatment.

A faultless effect is achieved owing to the repeated brushing-washing process as contemplated by this development, notwithstanding the protective treatment by virtue of the relatively limited effective time for each brush.

As already explained heretofore a further aspect of this invention relates to a novel apparatus for carrying out the inventive method. The inventive apparatus embodies a treatment section or housing containing rollers over which the textile web is guided. These rollers comprise a series of adjacently arranged upper rollers and a series of adjacently arranged lower rollers disposed in the treatment section which is filled with or contains the bath. The textile web is alternately guided about an upper roller and a lower roller as it moves through the treatment section. Individual brushes are arranged at least above the upper rollers, the bristles of which, in relation to an upper roller forming a support, extends over the entire width of the web guided past such brush and acts upon such web.

BRIEF DESCRIPTION OF THE DRAWING

The invention will be better understood and objects other than those set forth above, will become apparent when consideration is given to the following detailed description thereof. Such description makes reference to the annexed drawing wherein:

FIG. 1 schematically illustrates in sectional view a preferred construction of inventive apparatus for carrying out the inventive method;

FIG. 2 is a schematic sectional view of the apparatus depicted in FIG. 1, taken substantially along the line II-II thereof; and

FIG. 3 is an enlarged fragmentary view showing a detail of the equipment depicted in FIG. 1.

DETAILED DESCRIPTION OF THE PREFERRED EMBODIMENT

Referring now more particularly to the drawing, it will be recognized that a wet-treated textile web B which is to be cleaned, especially freed from undesirable solid particles, is continuously guided from the preceding treatment stage in the direction of the arrow A through an appropriate squeezing mechanism 1 and over a suitable tension regulator 2 into the treatment section or housing portion 3. This treatment section or housing portion 3 contains a series of adjacently arranged lower or bottom rollers 4 and a series of likewise adjacently arranged upper or top rollers 5. As illustrated, the textile web B is guided along a desired path of travel through the treatment section 3 alternately about a lower roller 4 and an upper roller 5, finally leaves this treatment section 3 via a deflecting roller 6 and through the agency of a further squeezing

mechanism 7 which continues to deliver the textile web B.

The treatment section 3 contains a soluble treatment liquid, such as a washing- or treatment-bath. At the upper edge of the treatment section 3 there is provided a support 8 for a cover member generally indicated by reference character 9. At the side walls of the cover member 9 there are arranged small cylinder units 10 which are braced upon supports 11 of the treatment section 3 and by means of which the spacing of the cover member 9 from the treatment section 3 can be varied in the vertical direction. In this way it is possible to adjust the spacing of brushes 12, to be considered shortly, arranged as a brush unit at the cover member 9, from the textile web B.

Now at the cover member 9 there are rotatably arranged a number of individual brush rollers 12, four being shown provided for the illustrated embodiment, these brush rollers being arranged in such a manner that two respective top or upper rollers 5 have associated therewith one such brush roller 12, as such can be best seen from the illustrations of FIGS. 1 and 3. The brush rollers 12 may be conjointly driven by means of a controllable drive motor 14 arranged at the cover member 9. Furthermore, any suitable adjustment means, as schematically indicated by reference character 20, may be provided so as to individually positionally adjust the brush rollers 12 relative to the textile web B.

Spray tubes or spray nozzles 15 are arranged between the brush rollers 12, by means of which a liquid jet or stream can be directed towards the contact line between the associated brush rollers 12 and upper rollers 5.

Cleaning, especially removal of undesired solid particles from the wet-treated continuously guided textile web B by means of the illustrated apparatus is carried out in the following manner: For the purpose of drawing-in the web B over the rollers 5 and 4, the cover member 9 is raised. After the web B has been drawn-in, the cover member 9 is again mounted, whereby in this position the bristles 12a of the brush rollers 12 always act at the locations of the textile web B at which the web bears at its opposite face or side upon one of the supporting rollers 5. The installation can now be placed into operation, whereby, for the purpose of transporting the textile web in the usual manner, the upper rollers 5 and/or the bottom rollers 4 can be driven through the agency of a non-illustrated slip coupling from one of the squeeze rollers of the squeeze mechanisms. Depending upon the desired effect the brush rollers 12 are placed into rotation by the drive motor 14 either with the textile web B leading or lagging.

Now during the subsequent operation of the equipment, as should be readily apparent, the textile web B will be successively guided past the brush rollers 12 and thus each time brushed over its entire width. Directly thereafter and before the next following brushing operation comes into play the textile web B is again immersed into the treatment bath, so that the particles which were freed or released by the prior brushing operation can be floated or flushed away.

At the effective region of the brushes the textile web B is always supported at the opposite face or side thereof. This results in the advantage that the brushing effect can be carried out independent of the fact whether the textile web is transported with a greater or

lesser tension, no creases or folds can appear and also the web cannot be shifted away.

Furthermore, as illustrated in FIG. 2, if the bristles 12a of the brush rollers 12 are additionally arranged in such a manner that the brush winding 17, in other words the arrangement of the wound bristles 12a on the brush rollers 12, extends in a screw-like or helical-shaped configuration from the center of the associated brush roller to both sides towards the ends of such roller, then by means of such construction of brush, during the brushing operation, there can be simultaneously produced a spreading or widening effect upon the textile web which markedly can counteract any tendency of folds or creases forming at such web.

With the arrangement illustrated in the drawings, the textile web B is always guided twice past the same roller brush 12.

Instead of using the illustrated rotating roller brushes 12 it would be also possible to employ stationary brushes. In both instances there is advantageously insured that the brushes, cannot only be adjusted as a unit together with the cover member 9 with regard to the textile web B but rather also that each brush can be adjusted or displaced within the unit or assembly and, as indicated by the mechanism 20 of FIG. 2, also can be exchanged, so that any possibly arising brush wear can be compensated or individual brushes within the assembly can be replaced for brushes having softer or harder bristles.

As should be readily apparent the illustrated embodiment of treatment apparatus provides a large number of variation possibilities. Thus, for instance, the textile web B can be also brushed at one or a number of locations where it is immersed in the liquid bath, in that for instance the housing portion or section 3 can be filled with liquid to a location above the height of the contact points between the brushes and the web. With equal facility the textile web could be, however, brushed in the free or surrounding atmosphere or if suitable measures were undertaken to hermetically seal the housing section 3, then the web could be brushed in any desired gaseous medium atmosphere.

If the housing section 3 is filled with liquid to a level beneath the brush rollers 12, then the textile web, following each brushing operation, is drawn through the liquid bath, so that any dry rubbing of the web by the brushes 12 is counteracted. The same purpose can also be achieved by a directed fluid stream or jet provided by the spray tubes or nozzles 15 (FIG. 2) impinging upon the brushing zone and by means of which there can be simultaneously attained an intensification of the cleaning action.

Due to the additional arrangement of brushes at the region of the lower rollers 4, as schematically illustrated by reference character 30 in FIG. 1 to denote one such lower arranged bristle brush, and by filling the housing section 3 with liquid up to a level beneath the brush rollers 12, it is possible to alternately brush the textile web at locations both within and externally of the liquid bath.

It can be, however, also desirable to guide both surfaces of the textile web B past at least one brush. This can be realized in a most simple manner if the one or the other or a number of the rollers 4 and/or 5 serving

as the support means of the textile web are themselves constructed as brush rollers, as schematically illustrated by reference character 4a and 5a for one of the respective lower and upper rollers 4 and 5.

Instead of using the illustrated separate drive for the brush rollers 12 by means of the drive motor 14, it would of course also be possible to carry out driving of the brush rollers, either in a direction which is the same as or opposite to the direction of transport or travel of the textile web, by employing the drive means which serves to drive or transport the web itself. Thus, for instance, any suitable schematically illustrated coupling 26 could serve to operably connect the brushes 12 with a drive unit 25 for the web B.

It is of significance to still here further mention that a "brush set or assembly" as such has been formed by the cover member 9 with the brush rollers 12 and the drive mechanism 14 is accommodated as a movable unit to the usual dimensions of the treatment sections 20 employed in the textile industry and can be arranged as a mountable unit at each such standard section.

While there is shown and described present preferred embodiments of the invention, it is to be distinctly understood that the invention is not limited thereto but may be otherwise variously embodied and practiced within the scope of the following claims. Accordingly,

What is claimed is:

1. A method for cleaning, especially the removal of undesired solid particles, from a wet-treated textile web, especially printed textile webs, continuously guided over rollers, comprising the steps of guiding the textile web in a supported fashion along a predetermined path of travel, then at short spaced locations along the path of travel of the textile web guiding the textile web over its entire width past individual brushes at locations thereof at the face of the textile web opposite the supported locations, brushing the textile web as it moves past such individual brushes, to thus achieve by means of the individual brushes a separate brushing effect at the respective locations of the textile web contacted by said individual brushes, simultaneous with the brushing operation subjecting the textile web to laterally applied forces to spread the textile web across its width, and immediately following the brushing operation flushing the textile web.

2. The method as defined in claim 1, wherein the step of flushing the textile web includes immersing the textile web into a treatment bath, and wherein the textile web is additionally brushed at least at one location in which such textile web is immersed in the liquid bath.

3. The method as defined in claim 1, including the step of guiding the textile web past brush rollers moving in the same direction as the direction of travel of the textile web.

4. The method as defined in claim 1, including the step of guiding the textile web past brush rollers which are moving in a direction opposite to the direction of movement of the textile web.

5. The method as defined in claim 1, wherein the widthwise spreading of the textile web is carried out from its central region towards the lengthwise edges of the textile web.
